GAS-FIRED REFRIGERATOR

Mark Shoeld, Baltimore, Md.

Application October 5, 1933, Serial No. 692,301

17 Claims. (Cl. 62—5)

The purpose of this invention is a gas-fired, aircooled, domestic refrigerator.

The primary advantage of a gas-fired refrigerator is its absolute silence and its freedom from wear. This invention makes it possible to produce a machine of this type at very low first cost and one that is very economical to operate.

In addition to the above, the major quantity of ammonia is always present on the low pressure side of the machine, which is of great advantage from a safety standpoint.

The only thing required for the operation of the machine is a small continuous gas flame. If desired the apparatus can be put in the cellar with the refrigerator in the kitchen on the next floor. The apparatus itself is, however, very compact and fits into a tiny space behind the refrigerator.

One object of this invention is an absorption refrigerator with a high pressure side and a low pressure side and with an intermittent generator, where the generator discharge and filling cycles are so short that the generating cycle is in operation nearly all the time.

Another object of this invention is an extremely small heat capacity of that part of the intermittent generator, which comes in contact with the liquor. This without the sacrifice of any structural strength of the generator.

Yet another object is a short cycle intermittent generator with a continuous heat supply.

Referring to the accompanying drawings: Fig. I is an elevation of the entire refrigerating machine; Fig. II is a somewhat enlarged cross section of Fig. I at A—A; Fig. III is an enlarged vertical cross section through the center of generator g, shown in Fig. I; Fig. IV is a horizontal cross section of Fig. III at B—B; Fig. V is an enlarged vertical cross section through the center of heater h, shown in Fig. I; Fig. VI is a horizontal cross section through heater h, as shown in Fig. V.

Fig. I shows a sideview of the entire assembly. This drawing is partly diagrammatic, but it is drawn to scale, so that the proper proportion of the various parts can be visualized. Referring to this drawing, g is the generator, h the heater, which in its operation is an integral part of the generator. r is the rectifier, c the condenser, e the evaporator and a the absorber.

The absorber a consists of two legs of standard 3" steel pipe with an overall height of 60". These pipes are provided with copper fins f, which is also indicated in Fig. II, which is a cross section at A—A of Fig. I. The 3" pipes are intercon-

nected at top and bottom with short pieces of 3" pipe, making a complete loop. A little below the top is another interconnection between the legs, the reason for which will be described later.

The evaporator e is shown on the side. In actual practice this part is of course in the ice box and would be behind the other apparatus.

The flow of the refrigerant is indicated with arrows, but merits the following preliminary explanation. The liquor in the generator g, during the generating cycle, is recirculated through the heater h, through pipes 5 and 4. Pipe 4 delivers a mixture of gas and liquor. Through pipe 6, the generator is charged with strong liquor and the weak liquor is discharged through pipe 7 to the absorber. These two pipes may under conditions be combined into one. The reason for using two pipes in this case will be shown later.

The gas from the generator passes through the rectifier r, which is equipped with copper fins, 20 The rectified gas goes through check-valve ch through pipe 3 to the condenser c, the construction of which will be described later. The condensed liquid ammonia goes through pipe 2, through a springloaded expansion valve ex into 25 the evaporator e. ic indicate ice-cube trays. The ammonia gas from the evaporator leaves through pipe 1 and goes to the absorber a.

b is a gasburner which burns steadily and continuously. The refrigerating effect as will be shown is a function of the size of the gas flame. The generator and heater assembly g and h is packed in insulating material as for instance infusorial earth or magnesia. This is indicated by i. s is the stack for the flue gases from the gas burner. This sheet iron stack is insulated with asbestos.

s is a stove pipe stack to carry away the hot air from around the rectifier fins. This air is warmer than the air from either the absorber or the condenser and it is carried away separately to the top of the machine so as not to interfere with the cooling efficiency of the absorber and condenser fins.

The generator-heater assembly is the heart of the machine and it will now be described.

A detail of a vertical cross section through the center of the generator g is shown in Fig. III. This drawing is also to scale. The inside diameter is 4 1/2" and the inside height 5 1/2". A horizontal cross section at B—B is shown in Fig. IV.

11 is a pressure resisting steel shell. The top 12 is shown bolted on. The numeral 13 indicates bolts. An aluminum or hard-lead gasket 14 is countersunk as is common practice in am-

monia flange fittings. It should be noted, however, that the top may be welded on. As a matter of fact the entire refrigerating apparatus assembly is welded steel.

5 An inside shell 15 of thin tin plate is provided and spaced evenly from the outside pressure resisting shell. The top of the inside shell is soldered to the outside shell at 16. Suitably a high melting point solder or pure tin solder should be used for this purpose. If the top 12 is welded on, it is of course necessary to also use welding for the inside shell instead of solder. In this case thin black sheet should be used for the inside shell instead of tin plate. A small "tin" pipe 17 leads 10 from the bottom of the space between the two shells at 18 to approximately the top of the inside shell.

19 is a cylindrical float valve with open bottom, which can slide up and down in vertical direction 20 on small "tin" pipe or aluminum rod 20. Stops 21 and 22, which are small discs fastened to 20 limits the travel of the float in relation to the center rod 20. The float position shown in Fig. III is its highest position. When disc 23, which is 25 an integral part of the float, strikes disc 21, the low position of float vs. rod is obtained.

The rod 20 carries valves 24 and 25 through pin joints 26 and 27. The travel of these valves is 30 limited to $\frac{1}{2}$ " and each is provided with its own 35 guide as indicated. As will be shown later, these two valves are never open at the same time. When one is closed the other one is open.

Disc 23 also operates liquor discharge needle 35 valve 28 through leverage arm 29. A screen s_2 is provided to prevent any clogging of the needle valve.

30 is a check valve at end of liquor line 6, which furnishes strong liquor to the generator from the absorber.

40 r is the rectifier, which consists of a 1" extra heavy steel pipe welded to the top 12 of the outside shell. It is provided with packing 31, which may consist of steel ball-bearing balls.

A vertical cross-section of the heater h is shown 45 in Fig. V and a horizontal cross-section in Fig. VI. These drawings are also to scale but shown in half size of Fig. III. The heater consists of a cylindrical piece of iron casting 5" diameter and 6" high with a spiral of two loops of $\frac{1}{8}$ " extra heavy 50 steel pipe cast into the periphery. This pipe ends up as pipe 4 and 5, the latter taking the liquor from the generator and the former delivering gas and liquor to the generator. This circulation of liquor is very rapid due to the "airlift" effect of 55 the gas produced in the heater section of the pipe. There are seven vertical $\frac{1}{2}$ " flues in the center of the casting. The heater rests on a refractory ring 32.

60 Going back to the generator in Fig. III, the dotted lines 33 and 34 indicate respectively the maximum and minimum level of liquor, corresponding to the beginning and the end of the generating cycle. The position of the float in 65 Fig. III shows that the generating cycle is about to start or is proceeding. This means that the liquor level is somewhere above the minimum 34. As indicated, valves 25, 28 and 30 are closed and valve 24 is open. The liquor leaves the generator 70 through pipe 5 and liquor and gas are returned through pipe 4. Pipe 4 terminates right inside the float, which acts as a splash or separating chamber. The end of line 4 is arranged so that the liquor and gas discharge is horizontal. The 75 gas leaves the inside of the float through pipe 10,

which starts slightly above the lowest level of the skirt of the float.

As the gas generation cycle proceeds, the liquor level recedes until it finally reaches level 34. At this point the weight of the float is sufficient to 5 open valve 28 through leverage arm 29. The weak liquor leaves through pipe 7 and is delivered to the absorber. After all the liquor has been discharged the pressure inside the generator drops and any condensate that has formed in the space 10 between the shells is ejected through pipe 11. The $\frac{1}{8}$ " heater pipe is also cleared of liquor. As the pressure drops further to a predetermined point, in this case 20# per square inch pressure differential between high and low side, the weight 15 of the float assembly makes it drop, opening valve 25 as it closes valve 24. Line 8 is a vent line which connects the top of the generator with the gas space above the liquor in the absorber. As soon as the pressures between the high and the low 20 sides have approximately equalized, check valve 30 opens due to the hydrostatic head of about four feet in the absorber, corresponding to about 2# per square inch pressure. The strong liquor from 25 the absorber flows into the generator through pipe 6. Some of this liquor also comes in through pipe 7, but the orifice at the valve 28 is of necessity so 30 small that it would take considerably longer time to fill the generator.

35 It might be mentioned here that there is constant circulation of liquor in the absorber due to thermosiphon action. It should be noted that the entire heat input into the absorber is at the lowest part of the right hand leg. This heat input is 40 from the hot weak liquor as well as from the absorption of the ammonia gas from the evaporator, which is introduced into the absorber through pipe 1. On account of this automatic circulation of liquor in the absorber, the weak liquor introduced into it through pipe 7 gets mixed up rapidly with the entire amount of liquor in the absorber. The quantity of liquor present in the absorber is about 30 times as large as the quantity of 45 weak liquor discharged from the generator in each cycle.

To prevent any slight noise when the weak liquor is discharged into the absorber, the pipe 7 running to the absorber may be extended into 50 the absorber in the form of a coil or return bends. This will precool the hot weak liquor and any 55 gas produced by the sudden pressure release will be condensed before it mixes with the liquor in the absorber. Any slight hissing noise at the orifice of valve 28 during the weak liquor discharge is effectively eliminated due to the fact that the generator is surrounded with insulating material.

60 As the liquor level rises in the generator during the filling cycle, valve 24 is kept closed due to the hydrostatic head in the generator until the top level 33 is reached, when the lifting power of the float is sufficient to counterbalance this hydrostatic head. The diameters of the float and the foot valve are so chosen, that at liquor level 33 the lift of the float corresponds to the weight of the entire float assembly plus $\frac{1}{4}$ of an inch extra liquor. At this point valve 24 snaps open as 65 25 closes. As mentioned before the maximum travel of these valves is $\frac{1}{2}$ ". At the same time valve 28 closes and due to the fact that the vent is closed, the check valve 30 also closes.

70 Liquor circulation between the generator and the heater starts as soon as valve 24 opens. Pres- 75

sure starts to build up in the generator and the generating cycle is on.

The generator emptying and filling cycle is a matter of about 30 seconds. The length of the generating cycle depends upon the refrigerating capacity desired and is a function of the size of the gas flame. The machine as shown with a refrigerating output corresponding to 75# ice per day, has a generating cycle of 20 minutes duration. The gas cock regulating the size of the flame is provided with a minimum and maximum stop. The lever of the cock is hooked up to a dial lever or "cold control", (not shown in drawings). If the apparatus is located in the back of the icebox, a usual bimetallic thermostatic gas shutoff control is provided to shut off the gas in case the flame blows out. If the apparatus is located in the cellar, the stack *s* is connected to the regular house chimney and the last mentioned safety arrangement is not required. The gas flame is on the order of only 3 c. ft. of 550 B. t. u. gas per hour for a refrigerating capacity corresponding to 75# ice per day. The average gas consumption is less than 1000 c. ft. per month of 550 B. t. u. gas.

Another safety control may be provided if so desired. This consists of a copper rod fastened to the heater casting *h* and extending out slightly beyond the insulation. At the end of the rod 30 a fusible alloy link and wire is attached. This wire holds a spring valve of the gas supply line open. If for any reason an excessive temperature is developed in the heater, the fusible link will part and shut off the gas.

The preferred expansion valve is of the spring loaded type and acts also as a safety valve for the high side. The high side of the apparatus is of relatively very small volumetric capacity in comparison to the low side.

Going back again to the generator shown in Fig. III, line 9 is a small auxiliary pipe directly connected with line 5 below valve 24 and extending slightly inside the float 19. The reason for this pipe connection is the following. After prolonged shut downs it is possible that due to any small leaks in the float it will fill or partly fill with liquor and settle down and close valve 24. In this case, when lighting the burner to start the refrigerator, liquor will be supplied to the heater through pipe 9. The gas and liquor discharge from pipe 4, will fill the float with gas and lift it, after which normal operating conditions ensue. In addition to using the inside of the float as a splash chamber, this is the reason for locating discharge end of pipe 4 in or under the float.

Before giving detailed data of performance of this machine under specific conditions, some further descriptions of various parts will be given.

The copper fins *f* of the absorber *a* shown in Figs. I and II extend the entire height of the refrigerator proper, that is minus the height of the refrigerator legs, which are not shown. The outside ends of the fins are closed off with vertical tin plate sheets 35. The purpose of this is to produce a stack effect by drawing in cold air from near floor level and discharging the warm air at the top of the refrigerator. This stack effect increases the heat transfer coefficient between the copper fins and the air, due to the increased air velocity over the fins. By far the largest amount of total heat to be dissipated is from the absorber.

The pipe connections 6, 7 and 8 to the absorber

are arranged to take a minimum of air space away from the copper fins. For this purpose the pipes are flattened to oval shape where they go through a split part of and are centered on a fin.

When generator *g* has just finished discharging liquor to the absorber *a*, the liquor level of the absorber is at its maximum and near the top. When the generator has just been filled, the liquor level in the absorber is at its minimum. The large pipe connection 36, shown in Fig. I, between the two legs of the absorber *a* is for the purpose of insuring a top liquor connection between the two legs under conditions of minimum liquor level, so that thermosiphon circulation of the liquor in the absorber takes place at all times.

Valves *v*, *v*₁ and *v*₂ are for the purpose of evacuating and filling the system with its original charge of ammonia and ammonia liquor. For this purpose a vacuum as nearly complete as possible is pulled at valves *v* and *v*₂. Liquid anhydrous ammonia is then introduced at *v*₂ until a pressure gauge at *v*₁ shows a certain predetermined pressure. Then ammonia liquor is introduced at *v* until it overflows at *v*₁. At this point the absorber is full of liquor to the top and the generator is full up to the top liquor level allowed by the float. Now a quantity of liquor is withdrawn from valve *v*, which quantity is somewhat larger than the volumetric liquor capacity of the generator *g*. The system is now filled and ready for operation.

At this point it may be well to explain the purpose of the inner shell 15 in generator *g*, shown in Figs. III and IV.

Just after the weak liquor has been discharged from the generator, the generator itself is of course at maximum temperature. When the strong liquor from the absorber *a* comes in through pipe 6 to the generator *g*, the inside shell only will be cooled down. This cooling of the shell (as well as float and valve assembly) is of course accomplished by evaporation of a small quantity of ammonia from the strong liquor, which returns to the absorber through vent line 8. The quantity of ammonia evaporated in this manner is a function of the heat capacity of the inside shell, float and valve assemblies inside the generator. By using an inside very light shell it will be shown later that the actual quantity of ammonia lost from the strong liquor to the absorber during the filling cycle is very small.

Referring to the rectifier *r* shown in Figs. I and II, it was previously mentioned that this consists of a piece of extra heavy 1" steel pipe filled with ball-bearing steel balls as packing 55 and provided with radial copper fins *f*. The copper fins are enclosed with a stove pipe stack *s*₁, which extends from the bottom of the fins to the top of the refrigerator, for reasons previously given. The outside diameter of this stack is 60 3 1/2" or the same as the outside diameter of the 3" standard steel pipes *a* of the absorber. Five radial copper fins 1" wide and 15" high are provided for heat dissipation from the rectifier.

The amount of ammonia in the condenser and lines 2 and 3 is relatively small. For this purpose lines 2 and 3 may be made from extra heavy 1/8" steel tubing with a steel wire in the center, filling most of the pipe. The condenser itself is made from two pieces of pipe. The outside one 70 is a 3" extra heavy steel pipe and the inside one is made for a slide fit. A relatively widely spaced thread is cut on the inside pipe which thread constitutes the passage for the ammonia. Top and bottom as well as all connections are flame 75

welded. The radiating fins of the condenser are identical with the fins of the absorber except for height.

The evaporator *e* is of double shell type, the refrigerant between the shells. It is arranged so that there is no chance for any water carried over with the ammonia to accumulate. The liquid ammonia enters through the expansion valve at the top. Rods or pieces of wire are welded lengthwise to the top half of the inside shell and to the bottom half of the outside shell to provide a zigzag path for the ammonia as it runs down both sides of the evaporator. The ammonia gas leaves from the lowest point. No check valve is required in line 1 from the evaporator to the absorber.

When a float control is used in generator *g* to operate the weak liquor discharge valve 28, the expansion valve *ex* is of the spring loaded type, which maintains a predetermined maximum pressure differential between the high side and the low side. This means that the required pressure exerted on the lever arm 29 by float 19 to open valve 28 is always the same. This in turn is a function of the liquor level in the generator. A predetermined liquor level in the generator at which point discharge valve 28 opens, means that the ammonia concentration of the weak liquor is always the same, when it is discharged into the absorber.

The above is the preferred arrangement. Valve 28 can, however, also be operated by means of a thermostat, either bimetallic or sylphon. In this case the expansion valve is of the diaphragm type, with one side of the diaphragm exposed to the atmosphere and the other side to the high pressure side. Any spring used for initial setting is in this case located on the atmospheric side of the diaphragm. This means that the expansion valve operates only on a predetermined basis of absolute pressure in the generator. With the absolute pressure constant in the generator during the generating cycle, the ammonia concentration in the liquor is only a function of the temperature. With predetermined setting of the thermostatic valve control, the weak liquor discharged to the absorber will always be of the same ammonia concentration.

The importance of maintaining predetermined ammonia concentrations of both the strong and the weak liquor is due to the fact that this is the governing feature of the efficiency of the refrigerator.

The spring loaded expansion valve *ex* in case of the refrigerator shown in the drawings operates when a pressure differential of 200# per square inch exists between the high and the low side. The force required to lift the liquor discharge valve 28 is one pound. The net area of the discharge line at valve 28 is 0.005 sq. in. or 0.08" dia. The leverage used in arm 29 is 1:4. The net weight of the float 19 when the liquor level is at 34 is 1/4#. At the moment valve 28 springs open, the pressure in line 7 and in the valve orifice is immediately increased. This causes the valve 28 to spring open without hesitation. The travel of the float is from disc 23 to disc 21 or about 3/8", which means that the vertical distance that valve 28 opens is 1/8" during the liquor discharge cycle. When the pressure differential between the high and the low side has dropped to 20# per square inch, the entire float assembly drops, opening valve 25 and closing valve 24. At this point all weak liquor has 75 of course been discharged from the generator.

The weight of the float itself is 150 grams and the weight of the entire float assembly is 225 grams or about 1/2#. Thus net dia. of opening in pipe at valve 25 is 0.18".

The above given figures determine the float dimensions to produce the maximum and minimum liquor levels 33 and 34. The level 34 is 10.8 centimeter above the bottom and the distance between 33 and 34 is 3.2 centimeters. The diameter of the float is 7.2 centimeters and the height 6.2 centimeters. The distance from the top of the float shown in the position of Fig. III to liquor level 33 is 1.5 centimeter.

It should have been mentioned previously that the concentration and temperature of the strong 15 and the weak liquor in this case are respectively 36% and 19% NH₃ at 114° and 300° F. This makes the specific gravity of both about the same or about 0.86.

The diameter of the foot valve 24 or rather the 20 diameter of the opening underneath is 1/8". This means that to open this valve at the end of the filling cycle a hydrostatic head of 1/4" liquor is required above the liquor level balancing the weight of the entire float assembly. The travel 25 of valves 24 and 25 is 1/8" as previously mentioned. It is therefore clear that there will be no hesitation in making the full stroke either up or down.

The total weight of the charge of strong liquor 30 in the generator at the beginning of the generating cycle is 1.5#. The total amount of weak liquor per cycle is 1.2#. The amount of ammonia available for refrigeration: 0.3# per cycle.

A specific example of a severe operating condition 35 and the efficiency of this refrigerator will now be given.

Room temp. 100° F.—Absorber and condenser temp.: 110° F.—Pressure differential between high and low side: 200# per square inch.—Condenser pressure: 247# abs.—Absorber and evaporator pressure: 47# abs. Liquor concentration in absorber: 36.7% NH₃ by wt.—Evaporator temp. 19° F.

(It should be noted that with the temperature 45 in the absorber normal or 80° F. for a 70° F. room temperature, the absolute pressure in the absorber and the evaporator will be 26#, corresponding to an evaporator temperature of -6° F. Obviously the NH₃ concentration of the liquor 50 in the absorber and the differential pressure between the high and the low side may be chosen to suit any desired evaporator temperature under given conditions.)

Temperature of weak liquor in generator right 55 before discharging to absorber: 300° F.—Concentration of weak liquor: 19.1% NH₃ by weight.—Amount of NH₃ lost during the filling cycle: 0.88% by weight of strong liquor. This is based upon 1.5# of strong liquor per charge and total 60 weight of inside shell in generator plus weight of entire float assembly and valves of 0.7#.

Net amount of ammonia available for refrigeration per 1# strong liquor: 0.207#. Concentration and temperature of liquor at end of 65 charging period: 35.8% NH₃ by wt. at 113.5° F.—Temperature at which NH₃ starts to go to the condenser under 247# abs. pressure: 215° F.

The following figures are on the basis of one 70 pound of strong liquor in the generator at end of charging period.

Amount of weak liquor at end of cycle: 0.793#.—Net amount of NH₃ available for refrigeration: 0.207#.—Amount of water returned from rectifier: 0.021#.

Heat required to raise temperature of liquor: 194.5 B. t. u. Evaporate and superheat 0.207# NH₃; 108.9 B. t. u.—Evaporate 0.021# water: 19.3 B. t. u.—Total heat input per one pound of strong liquor: 322.7 B. t. u.

Refrigeration produced by 0.207# NH₃ under the conditions given: 94 B. t. u. Thus thermal coefficient of this refrigerator under the above conditions: 29%.

With normal condenser and absorber temperature the thermal coefficient would be somewhat higher.

Using 550 B. t. u. gas as heat supply at 80% efficiency, it takes one c. ft. of gas to produce the refrigerating effect of one pound of ice, under the conditions given. This is a very high efficiency for an air-cooled, gas-fired, domestic refrigerator.

As previously mentioned, for 75# ice per day, the generating cycle is 20 minutes, the emptying and filling cycle 30 seconds.

The weight of the cast iron heater is about 35#. With heat input corresponding to 75# ice per day the rise in temperature of the heater during the filling cycle is less than 3 degrees F.

The heating coil in the heater has a surface large enough to require less than 10 degrees F. temperature difference between the liquor and the metal to produce 75# ice per day.

The heat capacity of the liquor in the absorber and the absorber itself is such that when one charge of weak liquor is dumped into it, the temperature rise is less than 6 degrees F.

In the above mentioned case of 100° F. room temperature and 75# ice per day, the mean temperature of the absorber is 110° F. The minimum is 107° F. right before the end of the generating cycle and the maximum 113° F. right after a charge of weak liquor has been dumped into it.

The radiating surfaces indicated for the absorber, rectifier and condenser are ample to take care of the condition in question.

Those skilled in this art will understand, that this invention is not necessarily restricted to the precise and exact details of the apparatus described, because these are subject to more or less radical modifications without departure from the substance and essence of the invention as defined by the appended claims and without sacrificing any of its substantial benefits and advantages.

I claim:

1. In an absorption refrigerating apparatus with a high pressure side and a low pressure side, an absorber, a condenser, means for supplying heat to liquid in one part of the apparatus, means for transferring said heated liquid to a second part of the apparatus, said second part being provided with a conduit to conduct refrigerant to the condenser and with means for intermittently transferring liquid to the absorber.

2. In an absorption refrigerating apparatus as set forth in claim 1 and including heat accumulator means as an integral part of said first part of the apparatus.

3. An absorption refrigerating machine with an intermittent type generator and a continuous heat supply, the generator assembly of which consists of a container, a heating device, conduits cyclically connecting said container directly with said heating device, and means for intermittently closing the passage way of said conduits, said heating device being provided with a heat accumulator.

4. An absorption refrigerating machine as set forth in claim 3, the heat capacity of said heat

accumulator being at least ten times as large as the heat capacity of the total amount of liquor present in the heating device at any time.

5. In an absorption refrigerating machine, an intermittent generator, said generator consisting of a container, a heating device, and conduits cyclically connecting said container with said heating device; means for circulating liquor from the container through the heating device and back to the container; a valve and valve operating means to periodically shut off the flow of liquor through the heating device, said valve and said valve operating means being entirely enclosed within said container.

6. In an absorption refrigerating apparatus, an intermittent generator, a continuous heat supply which heats a liquid circuit cyclically connected to the generator, means for intermittently stopping the circulation of liquid in said circuit; an absorber; means for completely preventing transfer of absorption liquid between the generator and the absorber during the generating period and means for substantially emptying the generator during each cycle of operation.

7. An absorption refrigerating machine with an intermittent type generator, the generator assembly of which consists of a container, a heating device, and conduits cyclically connecting the container directly with the heating device; means for circulating liquor from the container through the heating device and directly back to the container; an absorber; and means for intermittently discharging to the absorber substantially all the liquor in the container, the heating device and the conduits.

8. In an absorption refrigerating machine with a high pressure side and a low pressure side, an intermittently operating generator, a continuous heat supply, which heats a liquid circuit cyclically connected to the generator, means for intermittently stopping the circulation of liquid in said circuit; an absorber, and means for completely preventing transfer of absorption liquid between the generator and the absorber during the generating period.

9. In an absorption refrigerating apparatus, an absorber, an intermittent generator, said generator consisting of a container, a heating device, and conduits cyclically connecting the container with the heating device; means for circulating liquor from the container through the heating device and back to the container; valve means for periodically preventing flow of liquor through the heating device, during the period when the container is being filled with a fresh charge of strong liquor; and a second valve means to vent the top of the container to the top of the absorber during said filling period.

10. An absorption refrigerating machine with an intermittent type generator, the generator assembly of which consists of a container, a heating device, conduits cyclically connecting said container with said heating device; means for circulating liquor from the container through the heating device and back to the container; an absorber; valve means located entirely within said container, said valve means being operative to discharge an entire charge of weak liquor from the container to the absorber at a predetermined point of ammonia concentration in the weak liquor; and a second valve means located entirely within said container, said second valve means being operative to vent the top of the container to the top of the absorber at a predetermined point.

of pressure difference between the container and the absorber.

11. An absorption refrigerating machine with an intermittent type generator, an absorber, said generator consisting of a container, a heating device, conduits cyclically connecting the container with the heating device; valve means located entirely within said container, said valve means being operative to vent the top of the container to the top of the absorber at a predetermined point of pressure difference between the container and the absorber; a second valve means located entirely within the container, said second valve means being operative in conjunction with said first mentioned valve means, said second valve means being operative to close the outlet conduit from the container to the heating device.
12. In an absorption refrigerating apparatus, an intermittent generator, said generator consisting of a container provided with a heat insulating lining, a heating device, and conduits cyclically connecting the container with the heating device.
13. An absorption refrigerating machine with an intermittent type generator, the generator assembly of which consists of a container, a heating device, and conduits cyclically connecting the container with the heating device, said container being provided with an inside shell of relatively thin metal spaced from the outside pressure resisting shell.
14. An absorption refrigerating machine as set forth in claim 13, and including an open connec-

tion between the inside of said container and the space between the two shells; and means to discharge at each cycle any condensate formed in the space between the shells.

15. In an absorption refrigerating apparatus, an intermittent generator, said generator consisting of a container provided with a heat insulating lining, a heating device, and conduits cyclically connecting said container with said heating device, the outside of said container being heat insulated from said heating device. 5

16. An absorption refrigerating machine, the generator assembly of which consists of a container, a heating device, and conduits cyclically connecting said container with said heating device; said container being provided with an open float valve control; the conduit from the heating device to the container terminating under or inside the float, substantially as described. 15

17. An absorption refrigerating machine, the generator assembly of which consists of a container, a heating device, and conduits cyclically connecting said container with said heating device; said container being provided with an open float valve control; an auxiliary liquor supply 25 conduit from the container to the heating device, the inlet of said auxiliary conduit extending inside the said float, to eliminate any liquor accumulation inside the float, substantially as set forth. 30
